UNITED STATES PATENT OFFICE.

WALTER MUELBERGER, OF MAPLEWOOD, NEW JERSEY, ASSIGNOR TO NATHAN & COHEN CO. INC., OF NEW YORK, N. Y., A CORPORATION OF NEW YORK.

DESIGN FOR TEXTILE FABRIC.

Application filed February 19, 1923. Serial No. 5,204. Term of patent 3½ years.

To all whom it may concern:

Be it known that I, WALTER MUELBERGER, a citizen of the United States, residing at Maplewood, in the county of Essex and State of New Jersey, have invented a new, original, and ornamental Design for Textile Fabric, of which the following is a specification, reference being had to the accompanying drawing, forming part thereof.

The figure is a plan view of a textile fabric showing my new design, in which the stripes A represent a rippled or seersucker effect while the stripes B containing the figures C represent a smooth unrippled effect.

I claim:

The ornamental design for a textile fabric substantially as shown and described.

WALTER MUELBERGER.
